MARKING DEVICE FOR STRAND MATERIAL

Ernest K. Bauer, Meadville, Pa., assignor to
 American Viscose Corporation, Wilmington,
 Del., a corporation of Delaware

Application December 15, 1949, Serial No. 133,200

8 Claims. (Cl. 118—234)

1

This invention relates to an apparatus for marking continuously running strands. More particularly the invention relates to marking continuously running strands at regular and predetermined intervals, such strands, for example, as those of a warp sheet, and marking the same during the winding or other manipulation thereof, such as on a spool or beam. The purpose of the marking is to warn or advise subsequent operators of the length of the strands used during certain textile operations, such as in weaving, knitting, braiding, or the like.

It is an object of the present invention to provide a means for marking a continuously running strand while it is running at high speeds.

Another object is to provide a marking system which applies a controlled amount of marking medium to the high speed running strand.

Other objects and advantages of the invention will be apparent from the drawing and description thereof hereinafter.

In the drawing, the invention is shown as applied to a running warp, such as during beaming, and

Figure 1 is an end elevation of an apparatus embodying the invention as the same is associated with a warp as it proceeds on its way from a creel to a beamer.

Figure 2 is a plan view of the apparatus.

Figure 3 is a side elevation of the apparatus.

Figure 4 is a section on line A—A of Figure 2, and

Figure 5 is a view of an alternative embodiment of the invention.

Briefly, the operation of the invention is as follows: a rotatable drum, in contact with a viscous ink supply so that its surface remains covered with a certain amount of the same, said amount being controlled by a scraper bar, is placed under the running strand but not in contact with the same. A bar, transverse of the direction of travel of the strand, is placed above the strand and at regular predetermined intervals comes down and forces the strand against the top surface of the ink covered drum thus marking the strand. The transverse bar is actuated by a solenoid which in turn is actuated by a switch associated with an idler or measuring roll which is rotated by the strand or strands passing over the same and at the same linear speed. The solenoid may also be actuated by a switch associated with the driving connections for the spool or beamer or the means for feeding the strand or strands, such as the driving rolls, and the like. The solenoid may be actuated by an independent timing mechanism

2

if desired. Thus marks may be made on the strand or strands at any desired distance apart.

The marking medium may be of permanent or fugitive inks or dyes and may be applied to a single yarn as it is being wound into package form of conical, cylindrical or spherical shape for the purpose of indicating a definite yardage between successive marks. It may be applied to the warp as it is being wound on a beamer so that as the yarn is withdrawn in a loom, it is possible to determine when a certain length of fabric has been woven. The ink or dye must be used in viscous solution in order that the same will not penetrate or strike through onto several courses of yarns when wound, making it difficult to decide where the mark was made.

For a more detailed description, reference is made to the drawing which depicts the invention as the same is employed in connection with a warp. The invention will be described with reference to all five figures of the drawing.

In a roller housing 3, comprising end plates 3a and 3b there is rotatably mounted a shaft 3c to which is fixed, as by keying, a corrugated or grooved roller 4 so that its upper surface extends beyond the upper surface of the housing. If desired, the roller 4 may have a smooth surface. The housing is bolted to a horizontal metal plate 5 which in turn is fastened to a vertical plate 6 which rests on and is fastened to the horizontal metal plate or panel 7.

Adjacent one side of the housing structure is an ink receptacle 8 comprising a cylinder 9 with screw caps 10 at either end with a plunger 11 contained in the cylinder 9 operated by turning the handle 12. The ink, being in a viscous state, is forced by the plunger through the feed line 13 and through the ink inlet opening 14 extending across the surface of the roller 4. Thus, as the roller 4 is turned, its surface is covered with ink picked up by contact with the ink at the opening 14. Although the ink cylinder is shown with a hand operated plunger, any automatic hydraulic or pneumatic plunger may be employed so that a constant pressure on the viscous ink is maintained thus assuring an even supply of the same to the surface of the roller at all times.

On either side of the roller 4 and parallel to the same, are inverted U-guards 15 above which the warp thread 16 passes. The purpose of the guards is to prevent the warp thread from becoming entangled in the apparatus when the latter is forced down against the surface of roller 4. Positioned above the warp thread and transverse to its direction of travel, is a horizontal arm 17

capable of being raised and lowered in a vertical plane. In Figures 2 and 3 the arm 17 is shown in its raised position. Attached to one end of the arm 17 is a vertical rod 18 extending down below the roller assembly and attached at its lower end to a bell crank lever 19 pivoted at 20, the other end of which is fastened to the pivoted arm member 21 which is in turn fastened to the reciprocal rod 22 operated by means of the solenoid 23. Attached between one arm of the bell crank lever 19 and the projection 24 extending inwardly from the vertical plate 6 is a spring 25. The purpose of the spring is to return the bell crank lever to its original position when the solenoid is deenergized the operation of which is explained hereinafter.

The solenoid rotates the bell crank lever which in turn lowers the arm 17 against the warp thread 16 bringing the latter in contact with the roller 4. The roller 4 at the same time is rotated in a direction opposite to the direction of travel of the warp thread. This is accomplished by means of the movement of the arm 17. To the end of the arm 17, there is attached an arm or lever 26 by means of a washer 27 and cotter pin 28, the arm 17 extending through the elongated opening 29 in the lever 26 so that when the arm 17 is lowered it moves along the slot or elongated opening in lever 26 to the dotted line position shown in Figure 1. The other end of lever 26 is rotatably mounted on shaft 3c. A ratchet 30 is keyed to shaft 3c adjacent one end of roller 4. To the lever 26 there is attached a pawl 31 held down against the ratchet by means of the spring 32. Hence, when the arm 17 is lowered, the lever 26 is rotated thus turning the roll 4 in a counterclockwise direction by means of the ratchet 30 and pawl 31. To prevent the roller 4 from turning in a clockwise direction when the arm 17 is again raised, there is positioned on the lower side of the ratchet 30 a second pawl 33 held in position against the ratchet by means of the spring 34.

The distance through which the arm 17 travels is regulated or controlled by an adjustable stop adjacent the lower arm of the bell crank lever 19. The stop consists of a threaded socket set screw 56 extending downwardly through a threaded projection 57 extending outwardly from the apparatus framework, the socket set screw being locked in position and adjusted by means of the lock nut 58. The socket set screw 56 prevents the further counterclockwise motion of the bell crank lever 19 when the latter comes in contact with it and the distance of rotation is regulated by the distance the socket set screw extends beyond the projection 57 toward the bell crank lever 19.

In order to prevent too large an amount of ink from getting on the surface of the roller, there is provided a scraper bar 35 pivotally mounted at 36 and adjustable to and from the roller 4 by means of the screw 37 extending through the lower end of the scraper and seated in the roller housing 3 and acting against the spring 38 between the scraper and housing. The scraper insures the same amount of ink on the surface of the roller in contact with the strands of warp thread at all times. Any suitable scraping means may be employed such as a doctor blade, scraping bar, roller, and the like.

The energization of the solenoid 23 is preferably effected intermittently at intervals which correspond with known lengths of the strand or strands. Thus its energization may be derived from the driving connections for the spool or

beamer or the means for feeding the strand or strands. In the preferred embodiment shown, however, the energization of the solenoid 23 is derived from the idler or measuring roll 39. The measuring roll is driven by the strands passing over the same. The strands or yarns are in turn pulled through the apparatus from the creel by the positively driven beamer (not shown). Fixed to the shaft 40 carrying the measuring roll 39 is a pinion 41 in mesh with a gear 42 secured to shaft 43 carrying a disk 44 of insulating material provided with an outwardly extending projection or pin 45 of insulating material near the periphery thereof. Adjacent the disk 44 is a switch 46 which comprises a spring metal bar 47 securely fastened at one contact point 48 but not in contact with the other contact point 49 of the switch. As the disk 44 is rotated the projection 45 comes into contact with the metal piece or bar 47 forcing the same against the contact point 48 thus closing the circuit to the solenoid 23. When the projection 45 passes over the bar 47 the latter springs to its normal position opening the circuit to the solenoid 23. By means of this arrangement the solenoid 23 is actuated at regular intervals, e. g. each time roll 39 makes a predetermined number of complete revolutions. If desired roll 39 may be positively driven in which case a second roll 50 is employed in conjunction therewith as shown in Figure 5. Roll 50 is placed above roll 39 in the same plane and driven at the same peripheral speed. The yarn or other material is passed between the rolls 39 and 50 thus being driven or pulled through the marking mechanism.

The gears 41 and 42 are selected to give the desired yardage between energization of the solenoid 23 by the closing of switch 46 by the projection 45. These gears may be replaced by any form of conventional gear reducer to give the desired spacing between markings which may be frequent or widely spaced depending on the precise purpose of the marking.

The electric circuit for energizing the solenoid 23 comprises a line 51 connecting one terminal of the solenoid with switch 46, line 52 connecting the other terminal of the solenoid with one side of a current source 53, and a master control switch 54 in a third line 55 connecting switch 46 to the other side of the current source 53.

The operation of the above described apparatus is as follows: when the spring metal bar 47 closes the circuit to the solenoid 23, the arm 22 is shifted to the right, as viewed in Figure 1, this in turn rotating the bell crank lever 19 in a counterclockwise direction thus bringing the arm 17 down against the warp thread and to the dotted line position shown in Figure 4. In this position the strands come in contact with the corrugated or grooved roller 4 and by each strand falling into a groove on the surface of the roller it is completely submerged in the viscous ink. When the arm 17 moves downward, it rotates the roller 4 thus insuring a smooth, evenly inked surface when the strands come in contact with the same and at which time, i. e. strand contact time, the roller has ceased turning since the arm 17 has then come to rest in its lowermost position, shown by the dotted lines in Figures 1 and 4.

When the projection 45 moves past the spring metal bar 47, the solenoid 23 is deenergized and the spring 25 acting on the bell crank lever 19 rotates the same in a clockwise direction thus returning the arm 17 to its uppermost position,

shown in Figure 1, out of contact with the strands of warp thread. The warp thread, of course, returns to its natural traveling course through the apparatus shown by the solid line in Figures 1 and 4 above the guards 15 and roller 4. The marking system of the present invention may be employed in warp-knitting machines to control the relative speeds of two or more warp supplies, such as in U. S. 2,298,888 to Kaufman but without the necessity to mark the yarns during knitting. For this purpose, the frequency of marking of the several beams forming the source of supply for the several warps may be the same and adjustably-spaced observation stations similar to those of the patent may be provided. In the alternative the frequency of markings of the several warps may be related inversely to the rates of speed of the several warps so that coincidence of the markings of each warp occurs at definite intervals which may be timed at a single observation station or watched at two or more stations suitably spaced apart along the yarn travel.

It is to be understood that changes and variations may be made without departing from the spirit and scope of the invention as defined in the appended claims.

I claim:

1. Apparatus for intermittently marking a running strand comprising means for drawing a strand along a path, a roller for applying a marking material having its periphery adjacent one side of the path and normally out of contact with the strand in said path, a shaft for supporting the roller for rotation, said shaft and roller being mounted in a container, a pivotally mounted bell crank lever, electromagnetic means for rocking the lever, an arm pivotally mounted on the axis of the shaft and extending to a position beyond the other side of the path, a member interconnecting the lever and the arm for swinging the arm when the lever is rocked, means mounted on the arm comprising an element on said other side of the path for moving the running strand against the periphery of the roller when the arm is swung on its pivotal axis, means interconnecting the arm and roller for rotating the roller when the arm is swung to move the strand against the roller periphery, and means driven in synchronism with the running strand for intermittently energizing the electromagnetic means to control the frequency of contact between the strand and the roller.

2. Apparatus for intermittently marking a running strand comprising means for drawing a strand along a path, a roller for applying a marking material having its periphery adjacent one side of the path and normally out of contact with the strand in said path, a shaft for supporting the roller for rotation, said shaft and roller being mounted in a container, a pivotally mounted bell crank lever, electromagnetic means for rocking the lever, an arm pivotally mounted on the axis of the shaft and extending to a position beyond the other side of the path, a member interconnecting the lever and the arm for swinging the arm when the lever is rocked, means mounted on the arm comprising an element on said other side of the path normally out of contact with the strand in the path for moving the running strand against the periphery of the roller when the arm is swung on its pivotal axis, a ratchet connected to the roller for rotation therewith, a pawl extending from the arm and in engagement with the ratchet for rotating the roller when the arm is swung to move the strand against the roller periphery, and a timing roll driven in synchronism with and by the running strand for intermittently energizing the electromagnetic means to control the frequency of contact between the strand and the roller.

when the arm is swung to move the strand against the roller periphery, and means driven in synchronism with the running strand for intermittently energizing the electromagnetic means to control the frequency of contact between the strand and the roller.

3. Apparatus for intermittently marking a running strand comprising means for drawing a strand along a path, a roller for applying a marking material having its periphery adjacent one side of the path and normally out of contact with the strand in said path, a shaft for supporting the roller for rotation, said shaft and roller being mounted in a container, a pivotally mounted bell crank lever, electromagnetic means for rocking the lever, an arm pivotally mounted on the axis of the shaft and extending to a position beyond the other side of the path, a rod pivotally connected to the lever and to the arm for swinging the arm when the lever is rocked, means mounted on the arm comprising an element on said other side of the path normally out of contact with the strand in the path for moving the running strand against the periphery of the roller when the arm is swung on its pivotal axis, a ratchet connected to the roller for rotation therewith, a pawl extending from the arm and in engagement with the ratchet for rotating the roller when the arm is swung to move the strand against the roller periphery, and means driven in synchronism with the running strand for intermittently energizing the electromagnetic means to control the frequency of contact between the strand and the roller.

4. Apparatus for intermittently marking a running strand comprising means for drawing a strand along a path, a roller for applying a marking material having its periphery adjacent one side of the path and normally out of contact with the strand in said path, a shaft for supporting the roller for rotation, said shaft and roller being mounted in a container, a pivotally mounted bell crank lever, electromagnetic means for rocking the lever, an arm pivotally mounted on the axis of the shaft and extending to a position beyond the other side of the path, a member interconnecting the lever and the arm for swinging the arm when the lever is rocked, means mounted on the arm comprising an element on said other side of the path normally out of contact with the strand in the path for moving the running strand against the periphery of the roller when the arm is swung on its pivotal axis, means interconnecting the arm and roller for rotating the roller when the arm is swung to move the strand against the roller periphery, and a timing roll driven in synchronism with and by the running strand for intermittently energizing the electromagnetic means to control the frequency of contact between the strand and the roller.

5. Apparatus for intermittently marking a running strand comprising a rotatable roller, means for drawing a strand along a path above and normally out of contact with the periphery of the roller, a horizontal shaft for supporting the roller for rotation, a housing having a curved wall, said roller being mounted in the housing with an upper peripheral portion protruding therefrom and a lower peripheral portion disposed in close proximity to the curved wall along the entire lower peripheral portion, said wall having an elongated opening therein parallel to the axis of rotation of the roller, means for continuously forcing ink through the elongated

opening into contact with the roller periphery, a pivotally mounted bell crank lever, electro-magnetic means for rocking the lever, an arm pivotally mounted on the axis of the shaft and extending to a position above the path, a member interconnecting the lever and the arm for swinging the arm when the lever is rocked, means mounted on the arm comprising an element above the path normally out of contact with the strand in the path for depressing the running strand against the periphery of the roller when the arm is swung on its pivotal axis, means interconnecting the arm and roller for rotating the roller when the arm is swung to move the strand against the roller periphery, and means driven in synchronism with the running strand for intermittently energizing the electromagnetic means to control the frequency of contact between the strand and the roller.

6. Apparatus for intermittently marking a running strand comprising a rotatable roller, means for drawing a strand along a path above and normally out of contact with the periphery of the roller, a horizontal shaft for supporting the roller for rotation, a housing having a curved wall, said roller being mounted in the housing with an upper peripheral portion protruding therefrom and a lower peripheral portion disposed in close proximity to the curved wall along the entire lower peripheral portion, said wall having an elongated generally horizontal opening therein, means for continuously forcing ink through the elongated opening into contact with the roller periphery, a pivotally mounted bell crank lever, electromagnetic means for rocking the lever, an arm pivotally mounted on the axis of the shaft and extending to a position above the path, a member interconnecting the lever and the arm for swinging the arm when the lever is rocked, an element mounted on the arm above the path normally out of contact with the strand for depressing the strand against the roller periphery when the arm is swung on its pivotal axis, a ratchet connected to the roller for rotation therewith, a pawl extending from the arm and in engagement with the ratchet for rotating the roller when the arm is swung to move the strand against the roller periphery, and means driven in synchronism with the running strand for intermittently energizing the electromagnetic means to control the frequency of contact between the strand and the roller.

7. Apparatus for intermittently marking a running strand comprising a rotatable roller, means for drawing a strand along a path above and normally out of contact with the periphery of the roller, a horizontal shaft for supporting the roller for rotation, a housing having a curved wall, said roller being mounted in the housing with an upper peripheral portion protruding therefrom and a lower peripheral portion disposed in close proximity to the curved wall along the entire lower peripheral portion, said wall having an elongated generally horizontal opening therein, means for continuously forcing ink through the elongated opening into contact with the roller periphery, a pivotally mounted bell crank lever, electromagnetic means for rocking the lever, an arm pivotally mounted on the axis of the shaft and extending to a position above the path, a rod

5 pivotally connected to the lever and to the arm for swinging the arm when the lever is rocked, an element mounted on the arm above the path normally out of contact with the strand for depressing the strand against the roller periphery when the arm is swung on its pivotal axis, a ratchet connected to the roller for rotation therewith, a pawl extending from the arm and in engagement with the ratchet for rotating the roller when the arm is swung to move the strand against the roller periphery, and means driven in synchronism with the running strand for intermittently energizing the electromagnetic means to control the frequency of contact between the strand and the roller.

6. Apparatus for intermittently marking a running strand comprising a rotatable roller, means for drawing the strand along a path above and normally out of contact with the periphery of the roller, a horizontal shaft for supporting the roller for rotation, a housing having a curved wall, said roller being mounted in the housing with an upper peripheral portion protruding therefrom and a lower peripheral portion disposed in close proximity to the curved wall along the entire lower peripheral portion, said wall having an elongated generally horizontal opening therein parallel to the axis of rotation of the roller, means for continuously forcing ink through the elongated opening into contact with the roller periphery, a pivotally mounted bell crank lever, electro-magnetic means for rocking the lever, an arm pivotally mounted on the axis of the shaft and extending to a position above the path, a member interconnecting the lever and the arm for swinging the arm when the lever is rocked, an element mounted on the arm above the path normally out of contact with the strand for depressing the strand against the roller periphery when the arm is swung on its pivotal axis, means interconnecting the arm and roller for rotating the roller when the arm is swung to move the strand against the roller periphery, and a timing roll driven in synchronism with and by the running strand for intermittently energizing the electromagnetic means to control the frequency of contact between the strand and the roller.
